UNITED STATES PATENT OFFICE

135,719

DESIGN FOR A COMBINED TOY AIRPLANE AND PROJECTOR THEREFOR

Sidney J. Peers, Skokie, Ill., assignor to Chicago
Musical Instrument Co., Chicago, Ill., a corporation of Illinois

Application March 1, 1943, Serial No. 109,643

Term of patent 3½ years

To all whom it may concern:

Be it known that I, Sidney J. Peers, a citizen of the United States, residing at Skokie, in the county of Cook and State of Illinois, have invented a new, original, and ornamental Design for a Combined Toy Airplane and Projector Therefor, of which the following is a specification, reference being had to the accompanying drawing, forming a part thereof.

Figure 1 is a perspective view of a combined toy airplane and projector therefor showing my new design with a part of the projector in one position; and

Fig. 2 is a perspective view thereof with a part of the projector in another position.

The essential and characterizing features of the design are shown in full lines in the drawing.

I claim:

The ornamental design for a combined toy airplane and projector therefor, substantially as shown and described.

SIDNEY J. PEERS.
